HEAT EXCHANGE APPARATUS

John Adrian Churchill, Luton, and James Frank Belaieff and Cyril Terence Delaney, Cricklewood, London, England

Application November 29, 1944, Serial No. 565,660
In Great Britain November 15, 1943

4 Claims. (Cl. 257—125)

1

This invention relates to heat exchange apparatus and more particularly to heat exchange apparatus of annular form.

Annular or ring type radiators are known having radially disposed header tanks connected by arcuate tubes arranged about a common axis. This type of radiator has a special application in the case of aircraft wherein the space available for the radiator is very limited. A radiator of this type can be disposed around the propeller shaft. There are two kinds; namely, those wherein the cooling medium passes in a radial direction through passages between elements containing the fluid to be cooled, which may itself be a coolant in, for example, an engine, and those in which the cooling medium flows in an axial direction. With radiators of the latter type the arcuate tubes are of different lengths, those with the smallest radius being, of course, the shortest with the result that the rate of internal circulation will vary, and, in the case of oil, circulation may cease entirely in some tubes.

Another of the disadvantages with the radial flow radiator, however, with high speed aircraft is the sharp angle at which the incoming and outgoing cooling air has to be deflected. With the axial flow radiator there are two disadvantages; firstly, that the engine located immediately behind the radiator obstructs the free flow of air and necessitates a sharp deflection at the outlet, and, secondly, the length of air passages is limited and a long cowl is needed to secure an expansion between the inlet and the face of the matrix.

The object of the invention is to provide an improved form of radiator of annular type.

According to the present invention the plate heat exchange apparatus whilst of annular form has conical ends and the direction of the passages for the cooling medium has an axial as well as a radial component.

Referring to the drawings filed herewith:

Fig. 1 is a front elevation of one form of radiator made in accordance with the present invention;

Fig. 2 is a section on the line II—II of Fig. 1; and

Fig. 3 is an end view of one of the conical gills shown in Fig. 2 with the tubes in position.

Fig. 4 is an axial sectional elevation of a modified form of radiator;

Figs. 5 and 6 are end elevations, looking in the direction of arrows V and VI of Fig. 4, respectively, with cowling removed for ease of illustration of the radiator;

2

Fig. 7 is a fragmentary enlarged section of the matrix, taken on line VII—VII of Fig. 10;

Fig. 8 is a fragmentary sectional elevation of the radiator, through the air passages therein; and

Fig. 9 is a fragmentary sectional elevation of the radiator, taken on line IX—IX of Fig. 5.

Fig. 10 is a fragmentary sectional elevation of the matrix taken on line X—X of Fig. 4.

Fig. 11 is a fragmentary sectional elevation of the matrix, taken on line XI—XI of Fig. 9.

In Figs. 2, 4, 8, 9, 10 and 11, the thick lines represent the thickness of plates in section, which plates provide walls of tubular or other chambers, whilst the thin lines represent the ends or edges of plates in elevation and indicate an open end of a tubular or other chamber or a port in a wall through which fluid may flow. The open spaces bounded by said thick lines represent tubular or other chambers through which fluid may flow.

In Fig. 2 the engine (not shown) is presumed to be on the right with the propeller shaft projecting towards the left. Surrounding the propeller shaft and the usual variable pitch control and other mechanism is an inner fairing or engine cowling 3 and an outer cowling 13 forming between them an air passage 14 in which is positioned a cylindrical radiator block 5 drawn diagrammatically to show an inlet header tank 6 at one end and an outlet header tank 7 at the other end, each formed with a suitable coupling for connection in the circuits of the engine coolant or other fluid to be cooled.

The radiator block or matrix 5 comprises tubes 35 8 by which the header tanks 6 and 7 are connected and on which are disposed conical gills 9 which may be as shown in Fig. 3. The direction of flow through the radiator matrix 5 is indicated by the arrows 10. An additional outer cowling 4 is curved inwards at its forward end as at 12 to meet the front inner edge of the radiator matrix 5 and enclose the inlet header tank 6, and the cowlings 13 and 4 merge into each other at their rear edges. It will thus be seen that the radiator matrix 5 lies across passage 14 through which cooling air can pass in the direction shown by the arrows 15, the passage 14 being shaped to provide the least possible air resistance and to pass the air through the matrix 5. The passage 14 is dimensioned so that the maximum cooling effect is obtained from the air which enters it, and any excessive building up of pressure in said passage, with consequent spilling over of excess air at the mouth thereof, is avoided. Similarly, the arrangement permits the air used for cooling to re-

turn to the main air stream without producing harmful and disturbing currents.

It is to be understood that the plate heat exchange apparatus above described may be constructed in segments adapted to be detachably secured together in any convenient manner thereby facilitating removal, repairs or replacements and avoiding having first to remove the propeller.

In the form of the invention illustrated in Figs. 4 to 9 provision is made for two different fluids, either or both of which may be, for example, engine coolants, to be passed through the radiator whereby they are cooled by a cooling medium also passed through the radiator. For example, oil and water from the engine may be passed through the radiator so as to be cooled by air also passed through the radiator.

An annular radiator block or matrix 20 is disposed between inner and outer conical cowlings or fairings 21 and 22, respectively, in a manner substantially similar to that shown in Fig. 2 with reference to the matrix 5 and cowlings 3 and 13. Two annular header tanks 23, 24 are disposed, substantially concentrically, on the front end of the matrix and outside the outer cowling 22, and similarly two annular header tanks 25, 26 are disposed, also substantially concentrically, on the rear end of the matrix and inside the inner cowling 21.

The matrix comprises two series 27, 28 of nests of U-shaped passages. Each nest of passages is contained in a rhomboidal envelope 29, and the envelopes of the series 27 alternate with the envelopes of the series 28, each adjacent envelope being separated by corrugated or other plates 30 adapted to form passages 31 between said envelopes, as shown diagrammatically in Figs. 7 and 10. The U-shaped passages in each nest 27, 28 are disposed with their legs substantially parallel to the axis of the matrix, as shown in Fig. 4. The open ends 32 of the legs 33 of the tubes 27 are connected and open to the rear header tanks 25, 26, one leg to the header tank 25 and the other leg to the header tank 26, and with the base 34 of the U by which the two legs 33 are connected together arranged substantially radially of the matrix and in proximity to the outer conical cowling 22 remote from the said header tanks 25, 26, the arrangement being such that fluid may flow from one header tank 26 across the matrix through a U-shaped passage 27 and back to the companion header tank 25, the U-shaped passage 27 being disposed in a plane radially of the matrix. Similarly, the open ends 35 of the legs 36 of the passages 28 are connected and open to the front header tanks 23, 24, the U-base 37 of each passage being disposed adjacent the inner cowling 21; thereby, fluid may flow from header tank 24, across the matrix through the U-shaped passages 28 and back to the header tank 23.

The passages 31 formed by the plates 30 are disposed conically of the matrix 20, as shown in Fig. 8.

Water is led from the engine and is fed to the rear header tank 26 through inlet 38; it circulates through the nests of passages 27 and back to the header tank 25, whence it passes out through outlet 39 and back to the engine.

Oil is led from the engine and is fed to the front header tank 24; it circulates through the nests of passages 28 and back to the header tank 23 whence it passes back to the engine.

When the radiator is applied to an aircraft engine, and it is disposed in front of the en-

gine concentrically with the propeller shaft, it will be desirable that the conduits by which oil is transferred between the engine and the forward header tanks 23, 24 of the radiator should not interfere with the air flow through the cooling medium passage 58, hereinafter referred to, and associated parts of the aircraft. Preferably, therefore, two transfer boxes 40, 41 (Fig. 5) are disposed in the matrix, each substantially rhomboidal in shape, and in substantially similar positions to the nests of passages 27, 28, that is, in planes radially of the matrix.

The transfer boxes 40, 41 are preferably disposed side by side, and are each provided at the rear end with a port for connecting them to the oil system of the engine; for example, the oil inlet transfer box 40 is provided with a port 42 to which a pipe adapted to lead oil from the engine is connected, whilst the oil outlet transfer box 41 is provided with a port 43 to which a pipe adapted to lead oil back to the engine is connected. The transfer box 40 is provided at its forward end with a port 44 leading to the forward inlet header tank 24, but the said transfer box is blanked off at 45 from the outlet header tank 23. Similarly, the transfer box 41 is connected to the outlet header tank 23 but is blanked off from the inlet header tank 24. Each transfer box may be provided with longitudinal partitions 46 adapted to divide the box into a plurality of passages 47; said partitions may be formed by a corrugated plate disposed in the transfer box. By so providing the two transfer boxes 40, 41 the means for passing the oil to and from the forward header tanks are disposed within the matrix 20.

The passages 27, or 28 in a nest thereof may be disposed as shown diagrammatically in Fig. Fig. 4, with one U-shaped passage disposed between the legs of another so that they are disposed in one plane radially of the matrix in order to form a closely packed nest. The nest of passages may be formed within the rhomboidal envelope 29 by corrugated or otherwise shaped plates so as to space the sides of the envelope apart and form the said passages. The spacing plates may be disposed with the corrugations or ribs running longitudinally of the envelope with the exception of a triangular portion at one end wherein the corrugations are disposed transversely of the envelope, the effect being that each U-shaped passage is formed by two longitudinal corrugations, one at each side of the centre line of the envelope, and a transverse corrugation at one end of the envelope, the open ends of the said passages being disposed at the other end of the envelope, which latter end is open to the associated header tanks.

It will be obvious that each nest of passages may be otherwise suitably formed, for example, each U-shaped passage therein may be provided by an appropriately shaped tube, the tubes being held together to form a nest by conical gills or other means which may separate adjacent nests.

Whilst the form of device diagrammatically illustrated in Figs. 4 to 9 is provided with nests of passages 27 alternating with nests of passages 28, they may be arranged in any other suitable manner, for example, there may be two nests of water passages 27 disposed between adjacent nests of oil passages 28.

The radiator may be formed in two or more segments, for example as shown in Fig. 5, two semi-annual segments 48, 49, to facilitate removal from or assembly on the front of the en-

gine, the adjacent ends of the segments forming bulkheads 50, 51 between the segments. Each segment may form a separate radiator, or they may be connected together to form one complete radiator. For example, the engine oil may be passed from the engine to the segment 48 by way of the port 42 and the transfer box 40, thence to the forward inlet header tank 24, through the nests of passages 28 in the matrix 20 back to the forward outlet header tank 23 in that segment. A transfer pipe 52 (Fig. 6) is disposed at the forward end of the matrix across the bulkhead 50, and connects port members 53, 54 to each other; port member 53 is connected to the inlet header tank 24 in segment 48, and the port member 54 is connected to the inlet header tank 24 in segment 49; similarly, the outlet header tanks 23 in the two segments 48, 49 are connected to each other by port members 55, 56 and transfer pipe 57. Thereby oil is transferred from the header tanks in one segment 48 to the corresponding header tanks in segment 49. The oil then passes from forward inlet header tank 24 in the segment 49 by way of the nests of passages 28 in said segment to the associated forward outlet header tank 23, thence to the transfer box 41 and by way of the port 43 to the conduit for return to the engine.

The water from the engine may be passed in two separate streams, one to each segment 48, 49, each segment being provided with inlet ports 38 and outlet ports 39 to the rear header tanks 26, 25, respectively, so that each segment is a separate radiator with regard to water. Thereby, the oil flow will be in series through the two segments, whilst the water flow will be in parallel.

Air for cooling the water and oil in the nests of passages 27 and 28 will pass through the matrix 20 in a manner similar to that described with reference to Figs. 1 to 3; that is, the air will pass through the conical passage 58, formed between the cowlings 21 and 22, in the direction of the arrows 59 and in a substantially conical and expanding manner.

What we claim and desire to secure by Letters Patent is:

1. Annular heat exchange apparatus comprising an annular cylindrical matrix, a frusto-conical cowling at each axial end of said matrix with the smaller ends of the two said cowlings facing the same axial direction, the said cowlings defining a passage through the matrix for cooling medium which radiates from the axis of the matrix and progresses axially thereof the said passage being open on the inner and outer peripheries of said matrix, two annular header tanks disposed on each of said cowlings and on the side of said cowlings outwardly of said matrix, passages in said matrix for fluid to be cooled, said passages being disposed in cylindrical formation about the axis of said matrix, each of said passages being tubular and substantially of U-shape and being wholly disposed substantially in one plane radially of the matrix, the ends of one series of said passages being disposed in one of said cowlings and each of said passages in said

one series being open at its ends to the said two header tanks disposed on said cowling, the ends of another series of said passages being disposed in the other of said cowlings and each of said passages of said other series being open at its ends to the said two header tanks disposed on said other cowling, means for admitting fluid to be cooled to one header tank of each pair thereof mounted on each cowling, and means for withdrawing cooled fluid from the other header tank of each of said pairs thereof.

2. Annular heat exchange apparatus, according to claim 1, wherein groups of said one series of said U-shaped passages alternate around the said matrix with groups of said other series of said U-shaped passages.

3. Annular heat exchange apparatus, according to claim 1, wherein plates are disposed between said cowlings and in said matrix to form spacing members so as to separate groups of said U-shaped passages from each other around the matrix and to divide said passage for cooling medium into a plurality of smaller passages.

4. Annular heat exchange apparatus, according to claim 1, wherein two fluid transfer chambers are disposed within the matrix, each of said transfer chambers having one end disposed in one of said cowlings and being provided with a port at that end, the said port of one transfer chamber being adapted for admitting fluid to be cooled to said chamber, the said port of the other transfer chamber being adapted to allow cooled fluid to be withdrawn from said chamber, one of said transfer chambers being connected at its other end to one of the said header tanks disposed on the other of said cowlings and the other of said transfer chambers being connected at its other end to the other of said header tanks disposed on the said other cowling whereby fluid may be transferred from or to one end of said matrix to or from said header tanks at the other end of the matrix.
